UNITED STATES PATENT OFFICE.

JOHN F. MAKOWSKI, OF STOCKTON, CALIFORNIA, ASSIGNOR TO CALIFORNIA CEDAR PRODUCTS COMPANY, OF STOCKTON, CALIFORNIA, A CORPORATION.

PLASTER LATH.

Application filed October 27, 1924. Serial No. 746,058.

This invention relates to plaster lath of that type wherein finely divided mineral fragments are adhered to the surface of a base consisting of wall board of that type 5 wherein a core of plastic material is adhered between two surface sheets of heavy paper or the like.

The mineral fragments form the key for the plaster which is spread over the lath.

10 One of the essentials to a successful lath of the type under discussion is that the paper surface sheets be very firmly adhered to the core of the base board. Otherwise the weight of the gravel plus the plaster spread thereover would peel or tear such surface sheet from place and render the lath a failure.

15 The object of my invention therefore is to construct a lath of the type described in which an adhesive element is introduced into the core of the base board, which adhesive is of a special nature to mix with the plastic core in such a manner as to cause a practically inseparable bond between the core and surface sheets.

20 The figure of the drawing is a cross sectional view of a piece of plaster lath of the type under discussion.

25 Referring to the numerals on the drawings, 1 and 2 designate the surface sheets of thick paper or the like while the numeral 3 designates the interior core of the wall board to which the sheets are adhered.

30 In the past and before I commenced to use plaster board of this character as a base for plaster lath it was common practice to make the core of the wall board of gypsum plaster with saw dust or the like as a filler, the plaster predominating by volume. The adhesiveness of the plaster was relied upon to adhere the 35 surface sheets to the core.

35 Experimentation however proved to me that the adhesion of the paper to the core under the above method of making the board was insufficient to prevent the paper from 40 peeling off the core when the added weight of the mineral fragments, shown at 4 on the drawing, plus the plaster 5, was spread over the surface sheet. This was true even when a large volume of plaster and a minimum 45 amount of saw dust was used. A commercial lath however must be inexpensive and light and therefore in making the lath I

use about an equal amount, by volume of the saw dust or like filler, and plaster.

With these proportions when the material 55 is mixed with water into a moist semiliquid form for introduction between the surface sheets the mass lacks viscosity to such an extent that the gypsum (the adhesive) in the mass precipitates to the bottom. Thus as the 60 core hardens and sets the greater portion of the adhesive element will be adjacent one surface sheet only. Consequently the other sheet will not properly adhere to the mass and as any one of the surfaces may be the one on 65 which the mineral fragments 4 and plaster 5 may be adhered it is unsafe to use such last described board as a base for the lath, as the whole plaster key and plaster might peel off, particularly on ceiling work.

70 It is essential therefore that an element be introduced into the mass which will sustain all the ingredients therein in suspension while the same is hardening and setting.

75 After careful experimentation I have found that the properties of dextrin are such as to serve the purpose desired, and at the same time add greater adhesive qualities to the mass.

80 By thoroughly mixing the plaster, sawdust, water and dextrin together, the properties of the dextrin cause the mass to be viscous or glutinous to such an extent as to hold all the elements therein in suspension as a composite whole and positively prevent precipitation of the lime to the bottom. At the same time dextrin itself is an adhesive, so when the permeation of the surface papers is had there is a complete, uniform adherence between the mass and both surface sheets.

85 I have further found by experiment that by reason of the viscosity of the mass when mixed with the dextrin a much larger percentage of saw dust may be used in the board and this of course makes same lighter and 90 cheaper, which of course increases its commercial value. This advantage is permitted of because the tendency to precipitation of the lime being overcome, the slightly additional interstitial spaces formed by the introduction 95 of more saw-dust become of no consequence.

Then again the viscous dextrin tends to adhere all the ingredients together in their suspended relation which action causes the saw-

dust to remain uniformly distributed throughout the mass, whereas when plaster alone is used and the precipitation takes place the saw-dust tends to float more to the top, 5 which action also hinders the production of a perfect base board.

In addition to the above, the properties of dextrin are such that when mixed with the gypsum in the plaster it forms an insoluble 10 adhesive. This insolubility causes the mass to adhere closely to the papers commonly used for the surface sheets of the wall board. Furthermore the dextrin adhesive as thus used 15 will not soften under heat and for this and the above reasons will firmly hold the mass and the covering sheets together and will totally eliminate the troublesome "peelers".

This then permits the plaster lath to be

built up on a base board of the type described, 20 which lath will have an all key surface and be capable of holding the plaster or other applied finish in a most effective manner. Also such a lath can be manufactured at a cost to allow it to meet commercial price competition. 25

Having thus described my invention, what I claim as new and useful and desire to secure by Letters Patent is:

A plaster lath including a supporting member comprising plaster board having a center core containing dextrin as an adhesive to adhere the core to the surface sheets, and a plaster key of comminuted mineral fragments adhered to the outer face of one sheet. 30

In testimony whereof I affix my signature.
JOHN F. MAKOWSKI.
